UNITED STATES PATENT OFFICE.

FRANK H. ARMSTRONG, OF AUBURN, NEW YORK, ASSIGNOR TO CORONA TYPEWRITER COMPANY, INC., OF GROTON, NEW YORK, A CORPORATION OF NEW YORK.

SEGMENT CARRIER FOR TYPEWRITING MACHINES.

Application filed December 30, 1919. Serial No. 348,326.

To all whom it may concern:

Be it known that I, FRANK H. ARMSTRONG, a citizen of the United States of America, and a resident of Auburn, county of Cayuga, 5 State of New York, have invented certain new and useful Improvements in Segment Carriers for Typewriting Machines, of which the following is a full and clear specification.

10 This invention relates to improvements in segment carriers which are adapted to be vertically shifted to position the type bars for printing the different case characters. One of the main objects of the invention is 15 to provide a segment carrier which is vertically shiftable and formed with vertically arranged ball raceways, means being provided for holding the balls in said raceways and permitting them to have a limited vertical movement with the segment carrier.

Another object of the invention is to provide a sheet metal segment carrier having integral ball raceways formed at its ends and cooperating with complementary sheet metal 25 raceways supported in the machine frame.

Another object of the invention is to provide a vertically shiftable segment carrier with anti-friction bearing devices said devices serving as the means to lock the segment carrier to the machine frame and prevent horizontal movement thereof, said anti-friction devices permitting the desired vertical shifting movement of the segment carrier.

30 There are other important objects of the invention which will appear hereinafter.

In the drawings:

Fig. 1 is a perspective view of the segment carrier and its supporting brackets.

40 Fig. 2 a perspective view of the carrier detached from its supporting means;

Fig. 3 a horizontal sectional view of the rear portion of the machine frame and a portion of the segment carrier;

45 Fig. 4 a detail perspective view of one of the rigid brackets adapted to be secured to the machine frame and carrying the ball race;

Fig. 5 a detail perspective view of one of 50 the plates for securing a stationary ball race in position;

Fig. 6 a detail perspective view showing the inner side of the stationary ball race bracket, the ball supporting means being 55 shown in position;

Fig. 7 a detail horizontal view showing a modified form of the stationary ball race bracket and ball supporting means; and

Fig. 8 a detail perspective view of the modified form of ball support shown in 60 Fig. 7.

Referring to the various parts by numerals, 1 designates a type bar segment which is adapted to be secured to a segment carrier. 2 by means of screws 3 passing through the carrier plate and into the segment, as shown clearly in Fig. 3. It is obvious that the segment may be secured to the carrier by any suitable means and in any desired way. The segment is provided with 65 radial slots adapted to receive the ends of the type bars in the usual manner.

The segment carrier is preferably formed of sheet metal and comprises the back plate 4, which is arranged vertically of the machine and extends transversely thereof near the rear frame bar or wall 11. The carrier plate at its ends, as is shown in the drawings, is bent forwardly at right angles to the main portion of the plate, as indicated at 5. These forwardly extending portions 5 form raceway flanges in which raceways 6 are formed, said raceways being bent inwardly toward the longitudinal center line of the machine and formed V-shape in 70 plan view. At each end of the carrier plate are formed forwardly extending stiffening lugs 7, the outer edges of said lugs bearing against the inner edges of the raceways at the upper ends thereof, said lugs being preferably integral with the upper edge of the carrier plate. These lugs serve to stiffen the raceways and hold them against pressure 75 tending to force them inwardly. The carrier plate is also formed at its ends with forwardly extending lugs 8 which are integral with the lower edge of said plate. The lugs 8 are adapted to engage the lower ends of the raceways 6 to stiffen them and hold them against inward pressure. The forward edges 80 of the raceway flanges 5 are bent laterally outwardly to form flanges 9 which lie parallel with the main body of the carrier. The carrier plate is adapted to be shifted vertical to properly position the type bars for 85 printing the different case characters. The segment shifting means is not shown herein as it forms no part of the present invention.

To support the segment carrying plate in an upright position and to hold it against 90

horizontal movement, relatively stationary brackets are arranged close to each end of the segment carrying plate. Each of these brackets consists of a rear vertical plate 12 and a forwardly extending raceway flange 13 having formed therein the vertical raceway 14 complementary to the raceway 6 carried by the segment supporting plate. The flanges 13 lie close to the flange 5 when the parts are assembled, as indicated at Fig. 3, and the raceways thus formed are adapted to receive anti-friction balls 15. These balls serve as means for locking the segment carrying plate to the relatively stationary brackets, and hold said carrier against horizontal movement in any direction. They, however, permit a free vertical shifting of the segment carrier.

The brackets 10 form stationary raceway members which are secured to the rear frame bar of the machine by means of screws 16 which extend through said frame bar and into clamping plates 17 arranged on the inner face of the plates 12. Each plate 12 is formed with horizontal slots 18 through which the clamping screws 16 extend so that by loosening said screws the brackets 10 may be adjusted laterally on the frame bar to a limited extent to secure the proper adjustment of the raceway 14 to the raceways 6 on the segment carrier. Each clamping plate 17 is formed with a forwardly extending flange 19 through which extends horizontally arranged screws 20. The inner ends of these screws are adapted to bear on the raceway flanges 13 of the brackets to serve as means for laterally shifting the brackets after the screws 16 have been loosened.

The raceway flanges 13 are stiffened at their upper ends by forwardly extending lugs 21 formed integral with the upper ends of the plates 12. Formed integral with the lower ends of the plates 12 are forwardly extending bottom plates 22; and said plates are formed with upwardly extending projections 23 which engage the lower ends of the raceway 14 to stiffen the raceway flanges 13 at their lower ends.

To support the balls 15 in the vertical raceways and permit them to have the desired vertical movement each of said balls is mounted in a forwardly and rearwardly extending retainer bar 24 which is provided with a suitable aperture to receive the ball as shown clearly in Fig. 6. One of these retainer bars and its ball 15 is arranged near the upper end of the raceways and one near the lower end thereof. The rear end of each of these bars is provided with a slot 25 adapted to receive a lug 26 formed on the flange 13. The forward end of each of these retainer bars is slotted, as at 27, and is adapted to extend through apertures 28 formed in the forward flange

9 on the carrier plate. A cross bar 29 formed between the apertures 28 is received in the slot 27 and forms a pivotal connecting means between the forward ends of the retainer bar and the flange 9 of the vertically shiftable segment carrier. The rear end of each retainer bar pivots on the projection 26 extending through its slot 25. By these means each retainer bar is pivotally connected at its rear end to the stationary raceway bracket and at its forward end to the vertically shiftable raceway flange so that the retainer bars will have a limited vertical shifting movement and there will be a corresponding movement of the balls. It is also manifest that these retainer bars will hold the balls in their proper positions in the vertical raceway.

The segment carrying plate 4 is limited in its downward movement by screws 30 which are mounted in the lugs 8 and are adapted to contact with the bottom plate 22 of the stationary brackets. The segment carrying plate is limited in its upward movement by screws 31 which are mounted in the lugs 21 of the stationary raceway brackets, the lower ends of said screws being adapted to contact with rearwardly extending horizontal lugs 32 formed of the flanges 9, as indicated in dotted lines in Fig. 1. Screws 33 mounted in the lugs 32 serve to limit the intermediate or cap shift of the segment carrier, this intermediate shifting of the carrier being secured by means not shown and which form no part of this invention.

In Figs. 7 and 8 is shown a slightly modified form of the means for laterally adjusting the relatively stationary raceway bracket and a slightly modified form of ball retainer. As shown in Fig. 7 plate 12 is formed with a forwardly extending flange 34 along its outer vertical edge. Adjusting screws 35 extend through this flange and are threaded into the flange 19 of the clamping plate 17. On the screws 35 are arranged lock nuts 36. It is manifest that by loosening the screws 16 the stationary brackets may be adjusted inwardly or outwardly by turning the screws 35.

The ball retainer shown in Figs. 7 and 8 consists of a ring 37 formed at diametrically opposite points with laterally extending lugs 38, one of said lugs extending through an aperture in the relatively stationary raceway flange 13 and the other extending through an aperture in the raceway flange 5 of the vertically shiftable segment carrying plate 4. It is manifest that by this means the balls will be held in their proper positions in the vertical raceways and a limited vertical movement thereof will be permitted. In this construction of ball retainer it is desirable to have the lugs 38 fitting in their apertures so that there will

be a limited amount of lost motion between the parts.

From the foregoing it is manifest that the segment carrier will be formed wholly of sheet metal; that it will be light and easily manufactured by stamping operations and that the vertical shiftable part will be mounted on anti-friction devices which lock the shiftable part to the relatively stationary part and hold said shiftable part against horizontal movement in any direction. It is also manifest that by mounting the bearing balls near the upper and lower ends of the raceways the shiftable segment carrying plate will be prevented from tilting in any direction and a true vertical movement of the segment will be assured.

What I claim is:

- 20 1. In a typewriting machine a vertically shiftable segment carrying member, vertically arranged raceways at the ends of said carrying member, relatively stationary complementary raceways mounted in the machine frame, anti-friction balls arranged in said raceways, and individual ball retainers to receive the balls and connected at one of their ends to the relatively stationary raceways and at their other ends to the vertically shiftable member whereby the balls will have a vertical movement with the vertically shiftable member and will be maintained in their proper relative positions in the raceways.
- 25 2. In a typewriting machine a sheet metal segment carrying plate formed at its ends with vertically arranged integral ball raceways, horizontally arranged lugs integral with the carrying plate and bearing against the upper and lower ends of the raceways to hold them against inward pressure, a sheet metal raceway bracket adapted to be secured within the machine frame at each end of the segment carrying plate, a vertical raceway flange formed integral with said bracket, means for mounting the raceway bracket on the machine frame to permit a horizontal adjustment of said bracket toward and from the ends of the segment carrying plate, lugs formed integral with the raceway bracket engaging the upper and lower ends of the raceways formed upon said bracket, anti-friction balls in the raceways, and ball retainers holding said balls in their proper relative positions within the raceways.
- 30 3. In a typewriting machine, the combination of a support shiftable to change case and provided with raceways, relatively stationary means provided with raceways cooperating with the raceways on the support, rolling elements in the raceways, and individual retaining devices for the rolling elements pivotally connected with the support and the stationary means.

4. In a typewriting machine, the combination of a support shiftable to change case and provided with raceways, relatively stationary means provided with raceways cooperating with the raceways on the support, rolling elements in the raceways, and individual retaining devices for the rolling elements each provided with an aperture for receiving a rolling element and having a pair of oppositely extending lateral projections thereon, said support and stationary means being provided with cooperating pairs of apertures in which the projections on the retaining devices engage.

5. In a typewriting machine, the combination of a machine frame, a vertically shiftable sheet metal segment-carrying plate extending transversely of the frame in a vertical plane and formed at its ends with vertically disposed flanges of channel form in horizontal section, sheet metal members held to the frame and formed with channels cooperating with the channels on said flanges to form ball races, antifriction balls in said races, and individual sheet metal ball-retainers extending across the races and each pivotally connected at opposite ends thereof with said plate and the adjacent sheet metal member.

6. In a typewriting machine, the combination of a machine frame, a vertically shiftable sheet metal segment-carrying plate provided at its side edges with flanges extending fore and aft of the machine, said flanges being pressed inwardly toward the center of the machine to form vertical outwardly facing ball-channels, a pair of sheet metal brackets held to the machine frame having flanges extending fore and aft of the machine outside of the flanges on the plate provided with inwardly facing vertical ball channels cooperating with the channels on the plate flanges to form ball races, and balls in said races.

7. In a typewriting machine, the combination of a machine frame, a vertically shiftable sheet metal segment-carrying plate provided at its side edges with flanges extending fore and aft of the machine, said flanges being pressed inwardly toward the center of the machine to form vertical outwardly facing ball-channels, a pair of sheet metal brackets held to the machine frame having flanges extending fore and aft of the machine outside of the flanges on the plate provided with inwardly facing vertical ball channels cooperating with the channels on the plate flanges to form ball races, balls in said races, individual sheet metal ball retainers extending between the flanges on the plate and brackets and each having a ball-receiving aperture therein, and means pivotally connecting each retainer with a ball channel flange on the plate and a ball channel flange on the adjacent bracket at op-

- posite sides of the ball race formed by the channels in said flanges.
8. In a typewriting machine, the combination of a machine frame, a vertically shiftable segment carrier provided with vertically extending outwardly facing raceways, a pair of upstanding members mounted on the machine frame adjacent the ends of the carrier and provided with vertically extending inwardly facing raceways cooperating with the raceways on the carrier, balls traveling in said raceways, means for adjusting said upstanding members inwardly and outwardly, and individual ball-retainers each having laterally slidable and horizontal pivotal connections with said carrier and one of said adjustable members at opposite sides of one of said ball raceways.
- 20 9. In a typewriting machine, the combination of a support shiftable to change case, a guiding member, cooperating raceway channels on said support and member, means for adjusting said member transversely of the path of movement of the support, a ball in the raceway formed by said channels, a ball retainer extending across the raceway, and means pivotally and slidably connecting the ball retainer at opposite sides of the raceway with said support and member respectively to swing in the direction of movement of the support and permit relative movement between said parts transversely of the direction of movement of the support.
- 25 10. In a typewriting machine, the combination of a support shiftable to change case, adjustable guiding members for said support, said support and members having cooperating raceways thereon, balls traveling in said raceways, and ball-retainers for spacing and driving the balls each having sliding pivotal connections respectively with said support and one of said adjustable members.
- 40 11. A shiftable support for a type-bar segment comprising a sheet metal plate having a flat main body portion to which a segment is adapted to be secured, said plate having integral side portions extending at an angle to the plane of the main body portion and each provided with a longitudinally extending ball channel.
- 50 12. A shiftable type-bar segment support comprising a flat sheet metal plate having opposite side portions thereof bent at a right angle to the plane of the main portion thereof, each of said side portions being pressed inwardly intermediate the longitudinal edges thereof to form an outwardly facing ball-channel.
- 55 13. A shiftable type-bar segment support comprising a sheet metal plate having a flat body portion and integral end portions bent at an angle to the plane of the body portion, said end portions each having a longitudinal ball-channel pressed in one face thereof and said plate being provided with integral lugs engaging the opposite faces of said end portions to brace the same.
- 70 14. A shiftable type-bar carrier comprising a sheet metal plate having side portions thereof bent at an angle to the plane of the main body portion of the plate and formed with ball channels in one face thereof, and pairs of lugs on said plate, each pair of lugs engaging one of said side portions at longitudinally spaced points on the face thereof opposite that provided with the ball channel.
- 75 15. An antifriction sheet-metal guide member for shiftable type-bar supports having two angularly disposed walls one of which is provided with a ball channel in one face thereof and the other of which is provided with integral bracing portions engaging the other face of said channeled member.
- 80 16. An antifriction guide member for shiftable type-bar supports comprising a single piece of sheet metal bent to form two angularly disposed walls, one of said walls having a ball channel pressed therein, said piece of sheet metal having integral bracing portions for the walls.
- 85 17. In a typewriting machine, the combination of a machine frame, an upstanding support shiftable vertically in the frame to change case and provided with outwardly facing raceways, a pair of laterally adjustable upstanding guide members each having two angularly disposed vertical webs one of which is provided with transverse slots and the other of which extends transversely of the support and is provided with an inwardly facing raceway cooperating with the adjacent raceway on the support, balls in said raceways, a pair of clamping members each engaging one face of the slotted web of one of said guide members, and clamping screws extending through the slots for adjustably holding the guide members through the medium of said clamping plates.
- 90 18. In a typewriting machine, the combination of a machine frame, an upstanding support shiftable vertically in the frame to change case and provided with outwardly facing raceways, a pair of laterally adjustable upstanding guide members each having two angularly disposed vertical webs one of which is provided with transverse slots and the other of which extends transversely of the support and is provided with an inwardly facing raceway cooperating with the adjacent raceway on the support, balls in said raceways, a pair of clamping members each engaging one face of the slotted web of one of said guide members, and clamping screws ex-
- 95 100 105 110 115 120 125 130

tending inwardly through the rear wall of the machine frame and the slots in the guide members and threaded into the clamping members.

5 19. In a typewriting machine, the combination of a machine frame, an upstanding support shiftable vertically in the frame to change case and provided with outwardly facing raceways, a pair of laterally adjustable upstanding guide members each having two angularly disposed vertical webs one of which is provided with transverse slots and the other of which extends transversely of the support and is 5 provided with an inwardly facing raceway cooperating with the adjacent raceway on the support, balls in said raceways, a pair of clamping members each engaging one face of the slotted web of one of said guide 10 members, clamping devices extending through the slots in the guide members and connecting the clamping members with the frame, and adjusting devices connecting the clamping members and guide members for shifting said guide members laterally.

20. In a typewriting machine, the combination of a machine frame, a shiftable type bar support, a pair of guide members 30 for said support, said members being provided with inwardly facing raceways and said support being provided with complementary outwardly facing raceways, rolling elements in the raceways, means for releasably clamping the guide members to the rear wall of the machine frame, and adjusting screws carried by the clamping means for shifting the guide members laterally.

40 21. In a typewriting machine, the combination of a main frame, a substantially

flat support shiftable vertically edgewise in the frame closely adjacent the rear wall of the frame, a type segment held to said support, guides held to the rear wall of the 45 main frame, said guides and support being formed with cooperating raceways, and rolling elements in said raceways.

22. In a typewriting machine, the combination of a main frame, a substantially 50 flat sheet metal segment carrier shiftable vertically edgewise close to the rear wall of the main frame, sheet metal guides held to the rear wall of the main frame, said carrier and guides having cooperating vertical raceways formed directly therein, and rolling elements in said raceways.

23. In a typewriting machine, the combination of a main frame, a sheet metal plate shiftable vertically edgewise close to 60 the rear wall of the main frame, sheet metal guides supported on the rear wall of the main frame, said guides and plate being formed with cooperating raceways, antifriction rolling elements in the raceways, a type-bar segment held to the front face of said plate, and means for adjusting said guides to take up wear in the anti-friction bearings.

24. In a typewriting machine, the combination of a main frame, a sheet metal carrier plate shiftable vertically edgewise in the frame close to the rear wall of the frame, a type-bar segment held to the front face of said plate, and means held to the 75 rear wall of the frame for guiding said plate vertically and limiting the extent of upward and downward movements of the plate.

This specification signed this 22nd day 80 of December, A. D. 1919.

FRANK H. ARMSTRONG.
